PORTABLE ELECTRIC DRILL UNIT

Joseph Gottlieb, Jersey City, and Carl Woessner,
Bloomfield, N. J.

Application February 29, 1952, Serial No. 18,727

Term of patent 7 years

(Cl. D54—14)

To all whom it may concern:

Be it known that we, Joseph Gottlieb and Carl Woessner, both citizens of the United States and residing respectively at Jersey City, in the county of Hudson and State of New Jersey, and of Bloomfield, in the county of Essex and State of New Jersey, have invented a new, original, and ornamental Design for a Portable Electric Drill Unit, of which the following is a specification, reference being had to the accompanying drawing, forming a part thereof.

Fig. 1 is a side elevational view of a portable electric drill unit, showing our new design.

Fig. 2 is a top plan view thereof.

Fig. 3 is a rear end view thereof, as seen from the right of Fig. 1.

Fig. 4 is an elevational view showing the side opposite to that shown in Fig. 1.

Fig. 5 is a front end view thereof, as seen from the right of Fig. 4.

Fig. 6 is a bottom plan view thereof.

We claim:

The ornamental design for a portable electric drill unit, substantially as shown.

JOSEPH GOTTLIEB.
CARL WOESSNER.
